CLAIM

The ornamental design for a propulsion control system for ship with a display, as shown and described.

DESCRIPTION

FIG. 1 is a perspective view of a first embodiment of a propulsion control system for ship with a display;

FIG. 2 is a left side view thereof;

FIG. 3 is a right side view thereof;

FIG. 4 is a top plan view thereof;

FIG. 5 is a front elevational view thereof;

FIG. 6 is a rear elevational view thereof;

FIG. 7 is a perspective view of a second embodiment of a propulsion control system for ship with a display;

FIG. 8 is a left side view thereof;

FIG. 9 is a right side view thereof;

FIG. 10 is a top plan view thereof;

FIG. 11 is a front elevational view thereof; and,

FIG. 12 is a rear elevational view thereof.

The broken line showing is for the purpose of illustrating portions of the propulsion control system for a ship with a display which form no part of the claimed design.

1 Claim, 12 Drawing Sheets
